BOLTING MEANS FOR GRINDING MACHINES

Henry John Mankoff, Wichita, Kans.

Application July 10, 1937, Serial No. 152,964

1 Claim. (Cl. 83—11)

This invention relates to improvements in bolting means for substance ground by a machine and has for its chief object the ability of producing a finished product at one operation of grinding, that is to say, no by-products are produced in the course of grinding as the substance being ground undergoes a uniformity of comminution and bolting, the product is produced at a single run.

10 A further object of my invention is to provide a frame, semicircular in form and in which finely perforated sheets of metal may be placed and secured in working relation to a rotatable grinder trunnioned in the machine at the axis of 15 the frame, and the said frame being so arranged will also receive and firmly bind in like position, a finely woven wire screen as bolting means for all of the substance being ground.

A still further object of my invention is to 20 provide an adjustable frame as supporting means for a woven screen, clamping the entire peripheral edge securely to avoid intermediate sagging of the screen during the grinding process, the screen, however being free to vibrate, 25 facilitating its sifting or bolting efficiency.

These and other objects will hereinafter be more fully explained, reference being had to the accompanying drawings forming a part of this specification and in which like characters will 30 apply to like parts in the different views.

Referring to the drawings:—

Fig. 1 is a sectional view through the grinding machine showing the installation of the frame in working relation to the grinder.

35 Fig. 2 is a plan view of Fig. 1, the grinder removed and other parts of structure for convenience of illustration.

Fig. 3 is an end view of the frame.

Fig. 4 is a plan view of Fig. 3.

40 Fig. 5 is an end view of the screen, showing the bent position of its oppositely disposed straight edges.

Fig. 6 is a plan view of Fig. 5.

Fig. 7 is a vertical sectional view through one 45 end of the grinder housing and screen frame.

Fig. 8 is a similar view to Fig. 7, omitting the frame and screen.

Fig. 9 is a sectional view taken on line 9—9 in Fig. 3, one end of the frame removed.

50 Fig. 10 is an enlarged sectional view at the top of the frame, showing the method of bending the screen to its clamped position by a rocking movement of the hood enclosure for the hammer grinder.

55 My invention herein disclosed consists of a

frame element comprising two semi-circular ends 1, said end members being connected by angle bars 2 respectively, and a rod 3 medially connecting said end members, the said frame pendently supported by bolts 4, secured to said bars 5 and upwardly extending to engage through in-turned portions 5, of sides 6, the said sides having end units 7 secured thereto, functioning as an external housing for the base of the grinding machine, while the said frame is enclosed by an 10 internal housing 8, extending to and being connected to ends 7, respectively, and to said sides as at A, the last said housing to receive the ground substance bolted through screen 9, positioned on the inside of said frame and secured 15 therein as follows.

The said bolting screen may be cut or manufactured in width to extend flush with the outside of each arcuate end 1, of said frame and being curved to seat snugly upon the inside 20 periphery thereof, while each side extends a short distance above its respective bar 2 of the frame and is bent outward thereon as shown at B in Figs. 1 and 2.

The said bolting screen being thus placed on 25 the frame and secured thereto, as later described, will be positioned in working relation to a rotatable grinder X as shown in Fig. 1, and the positioning of which will automatically secure both end edges between the inner edge of the 30 semi-circular end members and their respective arcuate shoulders 7', against which the frame ends are tensioned by said bolts 4; and the outward bent portions of the screen as at B at each side are also automatically secured by rocking 35 hood 10 on its pivot C, to a closed position over grinder X, said hood being secured to snug engagement by anchor bolts 11, while the rim portions adjacent their respective sides of the screen will seat firmly thereon, securing the said 40 side portion rigidly to bars 2.

In Fig. 5 is shown a marginal edge portion of the bolting screen turned outward as shown by dotted lines B, one side of which it is convenient to turn downward on its respective bar, 45 while the other side is adjacent the hinged point of the hood. In the case of the latter, the edge of said hood, as shown by its dotted line of travel, will contact the upper edge of the screen, bending it outward and downward as shown by dotted 50 lines, as the hood is rocked to its closed position, clamping the same firmly to its respective bar member 2, while the other side is secured by the free edge of said hood resting thereon as shown in Fig. 1.

It will be understood that the drawings do not disclose the feeding and discharge principles of the grinding machine, but the same will be considered to make the structure as a whole operative.

The discharge comprises a blower and pipe arrangement therefor whereby an air blast is produced as ejecting means for the bolted substance to storage or other means of disposal.

10 It is now clearly shown that this invention resides in an adjustably positioned frame and means to secure a bolting screen in the body structure of a feed grinding machine in working relation to a rotatable hammer grinding cylinder; furthermore, the said adjustably positioned frame as constructed, will permit the installation of a finely perforated metallic sheet positioned in said frame and supported thereby, in which case, the said frame is placed on a lower plane, 15 and the securing of the sides and ends of said sheet is not required, however the said sheet is forced to conform with the arcuate interior of the frame by the hood contacting each side, forcing the same downward at the time of tensioning the anchor bolts heretofore described.

20 Attention is directed to the fact that the perforations of the metallic sheet are not as impervious as the finely woven screen with respect to bolting or sifting of the substance passing therethrough as ground, and the flexing tendency of the screen is a means to agitate it sufficiently to avoid congestion; and as heretofore stated, the woven strands of the screen afford a 25 finely interrupted surface against which the substance being ground will contact, co-operating with the grinding cylinder, and to maintain

uniformity of the arc of the screen, the peripheral edges thereof, are firmly secured to the frame as heretofore described.

Such other modifications may be employed as lie within the scope of the appending claim, and having fully described my invention what I claim as new and desire to secure by Letters Patent is:

25 A structure of the character described comprising a casing having rigid end members, side members connected with the end members, arcuate, inwardly extending flanges formed on the end members, the ends of said flanges terminating adjacent the upper edges of the end members, said side members having inturned horizontal flanges, a hood for said casing pivotally connected with one horizontal flange and adapted to close the upper end of said casing, means for locking said hood in closed position, a frame device arranged in said casing and comprising semi-circular end members rigidly connected in 30 spaced relation by angle bars at their upper ends, the upper edges of the semi-circular members formed upon an arc corresponding to the arc of the end flanges and adapted to engage therewith, a sheet of wire gauzing arranged in said casing with two opposite edges engaging beneath the end flanges, bolts carried by the said flanges and engaging the angle bars for rigidly binding the edges of the gauze between the end flanges and the arcuate upper edges of the frame ends, the 35 opposite edges of the gauze extending above the frame bars and bent thereover, said hood when in its closed position adapted to bind the free edges of the gauze upon the angle bars.

HENRY JOHN MANKOFF.
